UNITED STATES PATENT OFFICE

163,444

TOWEL BAR BRACKET

William M. Crook, Houston, Tex.

Application December 11, 1950, Serial No. 13,381

Term of patent 14 years

(Cl. D4—3)

To all whom it may concern:

Be it known that I, William M. Crook, a citizen of the United States of America, residing at Houston, in Harris County, Texas, has invented a new, original, and ornamental Design for a Towel Bar Bracket, of which the following is a specification, reference being had to the accompanying drawing, forming a part hereof, wherein:

I claim:

The ornamental design for a towel bar bracket, as shown.

W. MACK CROOK.
